Attorney.

UNITED STATES PATENT OFFICE.

JOHANN G. WALLMANN, OF OAKLAND, CALIFORNIA.

COMBINATION POLICEMAN'S TRUNCHEON AND EXTENSION PISTOL-BARREL.

1,009,358.

Specification of Letters Patent. Patented Nov. 21, 1911.

Application filed February 23, 1911. Serial No. 610,253.

To all whom it may concern:

Be it known that I, JOHANN G. WALLMANN, a citizen of the United States, residing at the city of Oakland, in the county of Alameda and State of California, have invented certain new and useful Improvements in Combination Policemen's Truncheons and Extension Pistol-Barrels, of which the following is a specification.

10 My invention relates to improvements in combination policemen's truncheons and extension pistol barrels.

15 The object of my invention is to provide a policeman's truncheon which may be used as an additional barrel for the pistol he may carry; which may be quickly and firmly attached to the pistol and readily detached therefrom.

20 Other advantages of the device as embodying my invention will hereinafter appear.

25 To said ends my invention consists in the construction and combination of parts shown in the accompanying drawing, described in the following specification and particularly pointed out in the appended claims.

30 In the drawing, Figure 1 is a side view of the policeman's truncheon embodying my invention as secured to a piston, which is shown in dotted lines. Fig. 2 shows partial sectional views of the truncheon. Fig. 3 is an end view of the handle of the truncheon. Fig. 4 is a view of inner parts of the handle of the truncheon in one position and Fig. 5 is a view of such parts in another position.

35 In the figures 1 shows a pistol having a sight 9 shown in Fig. 2.

40 10 is a cylinder, interiorly threaded, located in the handle of the truncheon having a catch consisting of a recess 21 and a lug 22 engageable with sight 9. An extension barrel 6, preferably of steel, running longitudinally in the truncheon, is provided at its rear end with a threaded flange 7 engaging interiorly the cylinder 10.

45 12 is a telescope joint on cylinder 10 having a forward wall 12' which is slidable and is centrally bored so as to inclose barrel 6 extending therethrough. A cylinder spring 13 encircles the barrel 6, one end thereof engaging wall 12' and the other end engaging fixed bearing 14 having a central bore in which barrel 6 fits, said spring keeping wall 12 in engagement with flange 7. The bearing 14 has a hole 29 in one side thereof 50 penetrated by rod 15 fixed in wall 12' and having a turnbuckle 16, the forward end of

said rod having wedge 18 engaging lug 32 of pivoted sight 5 and whereby the same is elevated and permitted to descend, a spring 20 fixed in the forward end of said truncheon engaging the forepart of said sight by means of head or pin 19.

55 A plug 17 is located in the forward end of handle 3, having threads engaging threads in said handle. The plug 17 has a hole in one side thereof in which is slidable rod 15.

The pistol 1 has a barrel provided with a forward end having less circumference than the body thereof designated 8 and fitting in 70 a corresponding aperture in flange 7.

75 A channel 30 in the forward part of the truncheon 2 contains rod 15 and in which said rod is slidable. A grooved sight 4 is provided in the knob of the truncheon handle 3. An opening 27 in the said knob is provided for sight 9 of the pistol 1. A hole 23, preferably tapered, in cylinder 10 is provided for engagement with the pointed head or pin 24 rearwardly engaged by cylindrical 80 spring 25 secured in the knob of said handle by screw 31.

85 To introduce the barrel of the pistol into the extension barrel 6, the same is inserted into the opening in the rear end of the handle of the truncheon provided therefor, sight 9 passing into the passage 26 until the sight contacts with telescope joint or sleeve 12, which is extended by spring 13 as shown in Fig. 4, the barrel of pistol 1, being then 90 turned to the right, the sight slides along the contacting edge of sleeve 12 until the sight is within the slot 21, when the pressure against sleeve 12 being relinquished, the sight is firmly held within the slot by lug 22 95 as shown in Fig. 5; thereupon the barrel of the pistol 1 is turned still farther to the right, head or pin 24 being thereby forced out of hole 23. The cylinder 10 being interiorly threaded as shown in Fig. 2 runs on 100 thread 11 of flange 7. The act of turning the pistol barrel to the right approximately $\frac{1}{4}$ of a turn draws the barrel of pistol 1 in so that the forward reduced end of said barrel fits firmly in its seat in flange 7 as 105 shown, making the bore of the pistol barrel and bore of extension barrel 6 one continuous bore. The act of turning barrel 1 to the right after being inserted in the rear end of the truncheon as set forth not only 110 makes a complete coupling of the two barrels mentioned, but sight 9 while being

drawn inwardly by the forward movement of cylinder 10 on the thread 11 forces inwardly sleeve 12, which simultaneously raises sight 5 by the act of wedge 18 being forced under pivoted sight 5 through the forward movement of rod 15. The act of turning the barrel of pistol 1 to the left until pin 24 enters hole 23 places the truncheon in a position to be uncoupled—said act clearing sight 9 from lug 22. The act of uncoupling the barrel of pistol 1 from the truncheon allows sleeve 12 to be forced backwardly by spring 13 until it contacts with flange 7. The sleeve 12 being moved rearwardly on account of the pistol barrel being withdrawn causes the wedge 18 to be withdrawn from under sight 5, resulting in the sight being depressed through the exertion of pressure by spring 20. The pin, which is engaged by spring 25 held in place in the knob of the truncheon by pin 31, when resting in hole 23 holds part 10 firmly so that when the barrel of pistol 1 is withdrawn the passage 26 is held in line with opening 27 for the withdrawal of the pistol.

Sight 5 is preferably given a coat of a suitable luminous substance which makes it possible to see it in the dark. The sight 5 disappearing as it does when the barrel of pistol 1 is uncoupled makes it possible to use the truncheon without cutting the person on whom it is used.

In constructing the truncheon embodying my invention, I prefer to follow the following method:—The forward part of the truncheon is of wood and is constructed in two parts, being glued to the barrel 6 and plug 17, the groove 30 being cut in the wood and fitted over the sight 5 and the sight rod 15 previously, thereupon the same is turned down while on barrel 6. The part 3 being a combination handle and case is made of aluminum and threaded to fit flange 17—it is plated to resemble gun metal finish to match the pistol barrel, and sight groove 4 is cut in the butt or knob of the truncheon. The turnbuckle 16 is for adjusting the sight 5. The part 2 is slightly tapered toward its forward end so that should it be grasped by an opponent it could easily be pulled out of his hand. Handle 3 has a large butt or knob as mentioned so as to make it improbable that the truncheon could be pulled from the hand of the officer having it in his possession.

I claim:—

1. In combination, a policeman's truncheon having an aperture extending longitudinally therethrough, a separate pistol barrel in said aperture, said barrel being provided rearwardly with an exteriorly threaded flange containing a chamber having a bore greater than the bore of said barrel extending forwardly from said chamber, an interiorly threaded cylinder inclosing said

threaded flange and having a rear wall containing a central opening, a sleeve having a forward wall containing a central opening slidably inclosing said barrel, and a spring engaging the front end of said forward wall. 76

2. In combination, a policeman's truncheon having an aperture extending longitudinally therethrough, a separate pistol barrel in said aperture, said barrel being provided rearwardly with an exteriorly threaded flange containing a chamber having a bore greater than the bore of said barrel extending forwardly from said chamber, an interiorly threaded cylinder inclosing said threaded flange and having a rear wall containing a central opening, a sleeve having a forward wall containing a central opening slidably inclosing said barrel; a spring engaging the front end of said forward wall, a rod connected to said sleeve rearwardly and having its forward end provided with a wedge, a pivoted slight in engagement with said wedge, and means bearing against said sight for keeping the same in engagement with said wedge. 80

3. In combination, a policeman's truncheon having an aperture extending longitudinally therethrough, a separate pistol barrel in said aperture, said barrel being provided rearwardly with an exteriorly threaded flange containing a chamber having a bore greater than the bore of said barrel extending forwardly from said chamber; an interiorly threaded cylinder inclosing said threaded flange and having a rear wall containing a central opening, a sleeve having a forward wall containing a central opening slidably inclosing said barrel; a spring engaging the front end of said forward wall; a rod connected to said sleeve rearwardly and having its forward end provided with a wedge; a pivoted sight in engagement with said wedge, a resiliently-supported pin projecting through the butt of the handle of said truncheon and engaging said threaded cylinder, and means bearing against said sight for keeping the same in engagement with said wedge. 95

4. In combination, a policeman's truncheon having an aperture extending longitudinally therethrough; a separate pistol barrel in said aperture, said barrel being provided rearwardly with an exteriorly threaded flange containing a chamber having a bore greater than the bore of said barrel extending forwardly from said chamber; an interiorly threaded cylinder inclosing said threaded end flange and having a rear wall containing a central opening; a sleeve having a forward wall containing a central opening slidably inclosing said barrel; a spring engaging the front end of said forward wall; a rod connected to said sleeve rearwardly and having its forward end provided with a wedge, a pivoted sight in en- 105

gagement with said wedge, a handle for said truncheon provided with a butt having a sight cut therein in alinement with said pivoted sight, and having also an interior 5 aperture for admitting the sight of a pistol therethrough, and means bearing against said pivoted sight for keeping the same in engagement with said wedge.

5. In combination, a policeman's truncheon having an aperture extending longitudinally therethrough; a separate pistol barrel in said aperture, said barrel being provided rearwardly with an exteriorly threaded flange containing a chamber having a bore greater than the bore of said barrel extending forwardly from said chamber; an interiorly threaded cylinder inclosing said threaded flange and having a rear wall containing a central opening and having 20 also a recess in the rear portion thereof centrally penetrated by a forwardly projecting lug and a passage on one side of said lug leading from said recess and extending through the rear end of said cylinder; a 25 sleeve having a forward wall containing a central opening slidably inclosing said barrel; a spring engaging the front end of said forward wall; a rod secured to said sleeve rearwardly and having its forward end provided with a wedge; a pivoted sight in engagement with said wedge; a handle for said truncheon provided with a butt having a sight cut therein in alinement with said pivoted sight, and having also an exterior 35 aperture for admitting the sight of a pistol therethrough, and means bearing against said pivoted sight for keeping the same in engagement with said wedge.

6. In combination with an extension barrel for firearms having its rear end provided with an exteriorly threaded flange having a central chamber therein opening rearwardly, an interiorly threaded cylinder having a rear wall provided with a central 45 opening therein of greater bore than said

first mentioned chamber and opening rearwardly, and having also a recess in the rear portion thereof centrally penetrated by a forwardly projecting lug and a passage on one side of said lug leading from said recess 50 and extending through the rear end of said cylinder; a sleeve having a forward wall provided with a central opening penetrated and slidably engaged by said barrel; a rod supported on one side of said barrel 55 having its rear end secured to said sleeve and its front end provided with a wedge, a pivoted sight rearwardly in engagement with said wedge, and means bearing against the front end of said sight for keeping it in engagement with said wedge.

7. In combination with an extension barrel for firearms having a rear end provided with an exteriorly threaded flange having a central chamber therein opening rearwardly, 65 an interiorly threaded cylinder having a rear wall, provided with a central opening therein, and engaging said flange, and having also a recess in the rear portion thereof centrally penetrated by a forwardly projecting lug and a passage on one side of said lug leading from said recess and extending through the rear end of said cylinder; a sleeve having a forward wall provided with a central opening penetrated and slidably 70 engaged by said barrel; a rod supported on one side of said barrel having its rear end secured to said sleeve and its front end provided with a wedge; a pivoted sight rearwardly in engagement with said wedge, and 75 means bearing against the front end of said sight for keeping it in engagement with said wedge.

In testimony whereof I affix my signature in presence of two witnesses.

JOHANN G. WALLMANN.
